UNITED STATES PATENT OFFICE.

JOHN C. GEBHART, OF ATLANTA, GEORGIA, ASSIGNOR TO ATLANTA UTILITY WORKS INC.,
OF EAST POINT, GEORGIA, A CORPORATION OF GEORGIA.

SAW-RECUTTING MECHANISM.

No. 888,704.

Specification of Letters Patent.

Patented May 26, 1908.

Application filed February 16, 1906. Serial No. 301,500.

To all whom it may concern:

Be it known that I, JOHN C. GEBHART, a citizen of the United States, residing at Atlanta, in the county of Fulton and State of Georgia, have invented new and useful Improvements in Saw-Recutting Mechanism, of which the following is a specification.

This invention relates to a machine for recutting the teeth in gin and linter saws, and embodies in its organization simple and effective elements for supporting the saw and imparting a rotary movement thereto with respect to a cutting device having a rocking movement, the operation of the several elements being controlled from a single shaft means.

The primary object of the invention is to provide a positively operating machine for expeditiously recutting gin and linter saws practically in an automatic manner, but without requiring particular attention to an operative except in applying and removing the saw with relation to a support therefor.

In the drawings:—Figure 1 is a side elevation of a machine embodying the features of the invention; Fig. 2 is a view similar to Fig. 1 looking at the side of the machine opposite that illustrated by Fig. 1; Fig. 3 is a transverse vertical section taken through the plane of the saw supporting means. Fig. 4 is a plan view of the machine having the scale with respect to the preceding figures slightly modified.

Similar numerals are employed to indicate corresponding parts in the several views.

The numeral 1 designates the bed of the machine having suitable legs or supports 2. The bed will be of such surface shape and body construction as to accommodate the application thereto of the several mechanisms which will be more fully hereinafter specified. On one end of the bed a shaft 3 is held in suitable bearings and provided with a band wheel or pulley 4, to which power may be transmitted from a suitable motive medium and also a balance wheel 5 which has an obvious function. The shaft 3 has a terminal crank 6 to which connection is made for controlling the rotatable feed of the saw, as will also be presently explained. Adjacent to the location of the shaft 3 a fulcrum support 7 rises from the bed 1, and has the upper extremity thereof so constructed as to embrace an intermediate portion of a rocker arm 8, the latter being held in the fulcrum

support by a suitable pin 9 on which it moves. At its outer end the rocker arm 8 is movably attached by a pin 9' to the upper extremity of a link 10, or crank means cooperating with the shaft 3. To the inner end of the rocker arm 8 a suitable punch 11 is removably secured and operatively disposed over a die block 12 also removably held in the upper end of a support 13 rising from the bed, and in the present instance illustrated as integral with the fulcrum support 7.

On the extremity of the bed opposite that supporting the shaft 3 a support 14 is located for holding the saw in proper relation to the die block 12 and punch 11. This support 14, as clearly shown by Fig. 3, has a base 15 held firmly on the bed and supporting a horizontally disposed gear 16, on the upper side of which, upper and lower clamping disks or members 17 and 18 are mounted, the gear 16 having a hub projection 19 extending into a lower socket 20 of the disk or member 18 and keyed or otherwise secured to the latter, as at 21, to insure a regular rotation of the clamping members with the said gear. Extending centrally through the clamping members and the gear, and also through the base 15 of the support 14 and the bed 1, is a bolt or clamping spindle 22 having its lower headed end 23 normally resting against a washer 24 applied to the under side of the bed over a slot 25 in the latter. This slot permits adjustment of the support 14 and the parts carried thereby towards and away from the die block 12 to compensate for saws of different diameters. The upper end of the bolt or clamping spindle 22 is provided with a nut 26 which maintains, when properly applied to the bolt or spindle, the several parts of the templet and the bed in operative association. Rising from the center of the lower clamping member or disk 18 is a hub or boss 27 having an upper reduced screw-threaded extremity 28 to receive a hand nut 29 which bears on the central portion of the upper clamping member or disk 17 and forces the latter towards the clamping member or disk 18, or against the saw that may be held between the two clamping members. The clamping member 17 has a central opening 30 to fit over the hub or boss 27, the diameter of said hub or boss being such as to permit saws to be readily disposed thereover and removed therefrom.

The gear 19 has motion imparted thereto

through the medium of a pinion 31 fitted over the upper extremity of a vertical spindle 32 secured in the base plate of the templet, as clearly shown by Fig. 3. The pinion 31 has an elongated depending hub 33 which extends downwardly through the inner portion of an arm 34 projecting from the templet, and also through a ratchet wheel 35, said hub being keyed or otherwise secured to the ratchet wheel so that movement of the latter will be positively imparted through the pinion 31 and the gear 19. The pinion 31 and ratchet wheel 35 rotate on the spindle 32, the gear wheel 19 and the clamping members or plates 17 and 18 being also free to rotate on the bolt 22. In the outer extremity of the arm 34 a pawl 36 is mounted, and thereto is attached the outer end of a rod or reciprocating bar 37, which connects with and receives its motion from the shaft 3. Through the operation of this rod or reciprocating bar 37 the ratchet wheel 35 is regularly rotated and the pinion 31 similarly operated in a like manner to actuate the gear 19 and the clamping members 17 and 18. By this means the saw held between the clamping members 17 and 18 is regularly rotated by a step-by-step motion over the die block 12.

The machine also includes means for removing the slight bur or fin from the under side of the saw which is caused by the cutting action of the punch. This attachment consists of a pillow block or support 38 held on the base 15 of the support 14 and provided in its upper portion with a suitable recess 39 to receive the base of an upwardly projecting socket block 40 having therein a pair of sockets 41 containing springs 42, the said sockets 41 having the lower extremities of pins 43 fitted therein and engaging the said springs. The pins 43 depend from the under side of a file holding head 44 comprising two members, one 45 of which is adapted to be clamped closely against the other 46 and secured by a clamping bolt 46. The upper end of the main part of the clamping head is formed with a recess or socket 47 to receive a file member 48 which is held in close contact with the under side of the saw with a yielding pressure owing to the pins 43 bearing upon the springs 42. The saw, after leaving the die block 12, and having burs or fins projecting from the teeth thereof in view of the operation of the punch, regularly

passes over the file member 48, and the latter removes the burs or fins and completes the operation of recutting the saw teeth. The pillow block 38 serves as a guide block in which the socket block 40 has reciprocating movement, the said block 40 having a rod or reciprocating bar 49 secured thereto and also to an eccentric 50 on the shaft 3. By this means the file head 44 is given a reciprocating movement with respect to the saw to render the file member 48 effective in removing the burs or fins from the cut teeth.

From the foregoing it will be seen that the machine is convenient in its operation, and that a saw may be regularly and beneficially recut thereby without requiring manual attention other than the application of the saw to or removal thereof from the templet or the clamping members of the latter.

Having thus fully described the invention, what is claimed as new, is:

1. In a machine of the class specified, the combination with saw tooth cutting devices, of a horizontally disposed rotatable saw supporting means, a reciprocatable filing mechanism adapted to bear against the under portion of the cut teeth of the saw with a yielding pressure, the said filing mechanism having an automatic vertical movement, and a single shaft for operating the cutting devices and filing mechanism.

2. In a machine of the class set forth, the combination with tooth cutting mechanism, of saw holding means having rotatable clamping members, means for imparting a step by step movement to the rotatable clamping members, a reciprocating block held adjacent to the saw holding means, a resiliently supported head carried by the said block, a file member removably mounted in the said head, and mechanism for operating the several parts, the file member being held with yielding pressure against the under side of the saw operated upon to remove the burs or fins formed by the tooth cutting mechanism.

In testimony whereof I have hereunto set my hand in presence of two subscribing witnesses.

JOHN C. GEBHART.
